TABLE LAMP

Albert N. Brooks, Chicago, Ill.

Application July 15, 1953, Serial No. 25,952

Term of patent 7 years

(Cl. D48—20)

To all whom it may concern:

Be it known that I, Albert N. Brooks, a citizen of the United States and a resident of Chicago, in the county of Cook and State of Illinois, have invented a new, original, and ornamental Design for a Table Lamp, of which the following is a specification, reference being had to the accompanying drawing, forming part thereof.

Fig. 1 is a perspective view of a table lamp showing my new design;

Fig. 2 is a top plan view thereof, the dotted-line representation of a lamp shade being omitted for convenience of illustration.

The dominant features of my design are shown in solid lines.

I claim:

The ornamental design for a table lamp, substantially as shown.
